UNITED STATES PATENT OFFICE

134,172

DESIGN FOR A FLAG OR THE LIKE

Louis Grudin, New York, N. Y.

Application August 21, 1942, Serial No. 107,991

Term of patent 7 years

To all whom it may concern:

Be it known that I, Louis Grudin, a citizen of the United States and a resident of the city of New York, in the county of New York and State of New York, have invented a new, original, and ornamental Design for a Flag or the like, of which the following is a specification, reference being had to the accompanying drawing, constituting a part thereof, in which

The figure is a front elevational view of a flag showing my new design.

I claim:

The ornamental design for a flag or the like, as shown.

LOUIS GRUDIN.
